COAL CRUSHER

Walter J. Armstrong, Columbus, Ohio, assignor to
The Jeffrey Manufacturing CompanyApplication November 2, 1926, Serial No. 145,830
Renewed March 8, 1934

12 Claims. (Cl. 83—53)

The present invention relates to certain new and useful improvements in coal crushers of the class adapted to the reduction of relatively large fragments of coal to a uniformly fine product of predetermined size at a single operation, by the co-operation of a toothed roller and a stationary concave breaker plate.

As heretofore constructed, machines of the class described have possessed certain inherent defects whereby an appreciable amount of oversized material escapes from the crushing machine with the finished product.

It is the especial object of this invention to provide an improved arrangement of parts whereby is secured greater uniformity of product without curtailing the capacity of the machine.

The means whereby I attain this object are fully set forth in the following specification, reference being had to the accompanying drawing of which

Fig. 1 is a side elevation of a coal crushing machine equipped with the devices of my invention.

Fig. 2 is a general plan view of the machine illustrated in Fig. 1.

Fig. 3 is a sectional view taken along the line III—III of Fig. 2.

Fig. 4 is a front elevational view of the extension shoe of the breaker plate.

Fig. 5 is a perspective view of the shoe illustrated in Fig. 4.

Like numerals refer to similar parts in the several figures.

In the drawing, the numeral 1 refers to a housing comprising the base frame, in which are formed the journal bearings 2 and 3, and the surrounding hopper portion for receiving the charge. In the bearings 2 and 3 are mounted the parallel horizontal shafts 4 and 5 respectively.

To one of the projecting ends of the shaft 4 is fixed a pulley 6 adapted to be connected by a suitable belt with any suitable and convenient source of rotating power to actuate the crushing machine. To the opposite end of the shaft 4 is fixed a spur pinion 7 which engages with the spur gear 8 attached to the projecting end of the shaft 5. Mounted upon the shaft 5 is the crushing roll 9 upon the periphery of which is formed crushing teeth 10, the size and arrangement of which is such that the intervening spaces have no dimension greater than the largest permissible fragments of the product.

At the upper forward parts of the main frame 1 is fixed a horizontal shaft 11 upon which is pivotally supported a concave breaker plate 12, the lower end of which is adjustably held by the eye bolts 13 in close proximity with the tops of the crushing teeth 10 to form, between the roll and the breaker plate, a downwardly tapering passage

through which the coal may be drawn by the

revolution of the roll to be crushed thereby. At the lower edge of the breaker plate 12 there is provided a shoe 14 formed of relatively hard material adapted to withstand the abrasive action of the coal as it passes through the crushing passage, and which may be readily renewed when worn.

When relatively large lumps of coal are fed to the machine the relatively small crushing teeth 10 are unable to drag them into the crushing passage, and such fragments tend to roll upon the surface of the crushing roll 9 without being broken thereby. To insure the breaking up of such large pieces of coal, and their passage through the machine, I have provided, at intervals upon the surface of the roll, relatively long hook shaped teeth 15 adapted to engage the large lumps of coal and drag them downwardly into the machine to be crushed thereby. In order that these longer teeth 15 may pass the breaker plate 12 without allowing the escape of oversized fragments of coal with the product, I have formed in the shoe 14, at the lower part of the breaker plate, grooves 16 arranged to register with and pass the long teeth 15. As heretofore constructed, the side walls of the grooves 16 have been parallel affording only a running clearance for the passage of the long teeth. When crushing certain kinds of relatively hard coal, relatively long and thin slabs and splinters of coal, presented edgewise to the grooves, have passed through without being broken, thereby mingling with the product, a considerable proportion of fragments having dimensions greater than the predetermined maximum limits.

According to the specific embodiment of the present invention as shown in the drawing, the grooves 16 have an initial imperforate portion and the side walls of the grooves diverge rearwardly. The imperforate groove portions are followed by portions which are interrupted by slots 18 which pass completely through the shoe or plate. Between the slots the grooved side walls are forwardly convergent so as to provide shearing edges or abutments 19. Slots 18 extend completely across the grooves and each slot, in one direction, is continued into the intermediate plate portion to provide a screen opening in association with the short teeth of the roll. As here shown, the slots are alternately thus extended in opposite directions so that the plate portions between the grooves is given a zig-zag conformation. Each slot is followed by a bottom abutment edge and lateral abutment edges which lie in the same generally radial plane.

In the operation of the machine, oversize fragments carried into the grooves by the long teeth of the closure roll engage the abutment edges and are consequently crushed, the crushed fragments passing through the screen openings in

the grooves. Material carried over the plate by the short teeth falls through the screen openings in the plate portions between the grooves.

It is to be understood that I do not limit myself to the precise construction here shown since the parts may be subject to wide variation as to details without departure from the spirit of my invention.

What I claim is:

10. 1. In a machine of the class described, the combination with a crushing roll having relatively small crushing teeth and relatively long feeding teeth, of a breaker plate positioned adjacent said roll and forming therewith a downwardly tapering passage through which material may pass to be crushed, grooves in the breaker plate adapted to register with and pass the feeding teeth, and slots extending through the breaker plate and transversely of said grooves adapted to 15 pass fragments of predetermined dimensions as and for the purpose set forth.
2. In a machine of the class described, the combination with a crushing roll having relatively small crushing teeth and relatively long feeding teeth, of a breaker plate positioned adjacent said roll and forming therewith a downwardly tapering passage through which material may pass to be crushed, grooves in the breaker plate adapted to register with and pass the feeding teeth, and slots extending through the breaker plate and transversely of the grooves, the edges of which constitute abutments against which material may be crushed by said feeding teeth as and for the purpose set forth.
3. In a machine of the class described, the combination with a crushing roll having relatively small crushing teeth and relatively long feeding teeth, of a breaker plate positioned adjacent said roll and forming therewith a downwardly tapering passage through which material may pass to be crushed, a concave extension of said breaker plate concentric with said roll adjacent the crushing teeth, grooves in said extension adapted to pass the crushing teeth and elongated apertures extending through said extension and transversely of said grooves adapted to 30 pass fragments of predetermined dimensions as and for the purpose set forth.
4. In a machine of the class described, a breaker plate having parallel grooves and escape apertures, said apertures being in the form of through slots extending across the grooves from points outside the grooves and providing bottom and side abutment edges in the grooves.
5. In a machine of the class described, a breaker plate having parallel grooves, each groove having transversely extending escape openings offset therefrom in alternate directions, the openings at one side of one groove extending between the openings at one side of the adjacent groove to form a zig-zag intermediate wall element.
6. In a machine of the class described, the combination with a rotary crushing roll having relatively small crushing teeth and relatively long feeding teeth, of crushing and screening means for cooperation with said roll; said means comprising a substantially imperforate portion disposed adjacent the bottom of the roll and provided with grooves in the rotational paths of said feeding teeth, and a perforate portion to the rear of said imperforate portion in the rotational direction of the roll, said perforate portion being characterized by slots extending in the axial direction

of the rotor and having grooves forming continuations of the grooves of the imperforate portion and interrupted by said slots.

7. In a machine of the class described, the combination with a rotary crushing roll having relatively small crushing teeth and relatively long feeding teeth, of crushing and screening means for cooperation with said roll; said means comprising a substantially imperforate portion disposed adjacent the bottom of the roll and provided with grooves in the rotational paths of said feeding teeth, and a perforate portion to the rear of said imperforate portion in the rotational direction of the roll, said perforate portion being characterized by slots extending in the axial direction of the rotor and having grooves forming continuations of the grooves of the imperforate portion and interrupted by said slots, the groove portions intermediate said slots having rearwardly diverged side walls.

8. A breaker plate for crushing machines provided with a plurality of spaced-apart diverging grooves, a plurality of series of shorter diverging grooves each series in alignment with one of the first named grooves, and an abutment at the beginning of each of said shorter grooves.

9. In a machine of the class described, a rotor having short and long teeth and breaker means cooperative with said rotor, said breaker means having grooves therein in which the long teeth of the rotor are received, said breaker means having through slots extending entirely across the bottom of said grooves and providing abutment edges for cooperation with said long teeth, said slots serving as means for the escape of material from the reducing zone of the machine.

10. In a machine of the class described, a rotor having short and long teeth and breaker means cooperative with said rotor, said breaker means having portions for cooperation with the short teeth separated by depressed ways in which the long teeth are received, said ways being intersected by through slots extending in the axial direction of the rotor, said slots having edges which serve as side and bottom abutment means for cooperation with said long teeth and the slots serving as means for the escape of material from the reducing zone of the machine.

11. In a crusher, the combination with a housing, of a rotary crusher roll therein having thereon long and short teeth, a yieldable breaker plate having grooves for the long teeth, a screening device comprising grooves for said long teeth with screen openings in the bottoms thereof and screen plate portions between said grooves, and shearing abutments in the grooves to cooperate with the long teeth to pulverize material for passage through the screen openings in the bottoms of said grooves.

12. A crusher and a screen device comprising a member having an arcuate groove adapted to receive a rotary crusher tooth, the side walls of said groove being provided with substantially radial shearing abutments in position to coact with said tooth, the bottom of said groove having transverse shearing abutments with shearing edges substantially in the planes of the shearing edges of the first named shearing abutments, the bottom of said groove also having screen openings bounded rearwardly, as regards the direction of movement of the crusher tooth, by said transverse shearing abutments.

WALTER J. ARMSTRONG.
